(Cl. D2—24)

The figure is a plan view of a brassiere showing my new design.

The dominant feature of my brassiere design resides in the combination on the brassiere disclosed of cup members having their outer bottom edge portions extending in a substantially straight line out from the bottom center of the round of each cup, and a substantially straight line continuation thereof which ends along the upper edge of the back band of the brassiere, together with a triangular insert section with its bottom edge at such line and its front edge along the cup side seam, all as shown.

I claim:

The ornamental design for a brassiere, as shown and described.
